UNITED STATES PATENT OFFICE.

FREDERICK JOHN GARNIER, OF ST. HELIER, JERSEY, BRITISH ISLES.

SLIDING WINDOW.

1,386,859.

Specification of Letters Patent.

Patented Aug. 9, 1921.

Application filed May 6, 1920. Serial No. 379,311.

To all whom it may concern:

Be it known that I, FREDERICK JOHN GARNIER, subject of the King of Great Britain and Ireland, residing at 16 Halkett street, 5 St. Helier, Jersey, British Isles, have invented a new and useful Improvement in Sliding Windows, of which the following is a specification.

This invention relates to improvements in 10 sliding windows and the like and more particularly to the means for retaining the window sashes in the desired open or closed position.

The usual method of supporting sliding 15 window sashes consists in the employment of sash cords and counterbalance weights. This method has many disadvantages inasmuch as when one or both of the sash lines become broken the window sash has to be re- 20 moved and part of the window frame dismantled to enable a new cord to be fitted. Moreover the sashes are a very loose fit in the frame so that a tendency to vibrate or rattle very often results, especially when the 25 window is partially open.

The object of the present invention consists in a simplified construction of means for retaining or supporting the window sashes in their desired position, without the 30 use of sash cords and weights, said means also securing the sashes against vibration during windy or rough weather.

According to the invention, I provide each 35 sash on each side of the window frame with a loosely mounted rotatable roller or the like which is adapted to be pressed into frictional contact with the vertical sides of the window sash by a spring or weight, an annular ring or sleeve being preferably arranged in such 40 a position as to extend between the roller or the like and the sash. The roller is preferably mounted in a sliding fitting comprising a forked member suitably guided in a supporting frame or casing. The frame may 45 also be provided with a removable back plate against which the rear end of the spring or springs (where springs are used), rest, said plate being easily removed so as to enable a broken spring to be replaced if desired.

50 In order that the invention may be readily understood reference is made to the accompanying drawings in which:—

Figure 1 is a front elevation of an ordi-

nary sash window having the invention applied thereto.

Fig. 2 is a vertical section on the line A—A of Fig. 1 with the sashes removed.

Fig. 3 is a horizontal section on the line B—B Fig. 2 of one of the fittings.

Figs. 4 and 5 are sectional view and elevation respectively of one of the fittings.

Figs. 6 and 7 are similar views of a modified construction.

The construction shown in Figs. 1 to 5 comprises a frame *a* in which is mounted 65 two vertically slidably sashes *b*, *c* said sashes being guided in the usual manner between guides *e*, *e*. The vertical side members *a*¹ of the window frame are each provided with a recess or aperture to receive a supporting 70 frame or casing *f*, one frame being provided on each side of each sash. These frames comprise side members *g* between which is mounted a rotatable roller or the like *h* carried between the ends of a forked or U- 75 shaped member *i*. This forked member is formed or provided with a rearwardly extending pin or the like *k*, the outer end of which passes through a hole in the rear portion *g*¹ of the frame. The pin *k* carries a 80 spring *m* normally tending to press the roller *h* toward the side of the window sash.

Between the roller *h* and the sash is mounted an annular ring or sleeve *n*. This sleeve is preferably of such size that part of 85 its periphery passes freely between the sides *g*, while its diameter is sufficient to permit the remaining portion of its surface to extend clear of the supporting frame as shown in Figs. 4 and 5. The end of the pin or the 90 like *k* is preferably screwed to receive a nut or the like *o* to limit the inward movement of the roller, and permit the tension of the spring to be adjusted.

In order that the roller *h* is suitably 95 guided, its spindle *h*¹ is preferably extended to opposite ends to engage with slots *g*² formed in the sides *g* of the supporting frame.

In the construction shown in Figs. 6 and 100 7 the spring *m* presses at its outer end against a removable plate *p*, the upper and lower edges of which are curved or bent to embrace pins *q*, extending through the sides *g*. These pins may be secured by locking 105 pins passed transversely therethrough at

their ends outside the members *g* or if necessary they may be formed by screwed bolts or in any other suitable manner. This construction permits the springs *m* to be easily replaced in case of breakage.

The front end of the supporting frame is provided with a flanged plate *r* or the like adapted to be screwed to the window frame, said plate being provided with a suitable 10 aperture or slot through which the sleeve *n* projects.

The details of construction may if necessary be modified without departing from the principle of the invention.

15 It will be seen that when in operation, each of the window sashes is supported by the rollers pressing inwardly toward the opposite vertical sides thereof. In this manner not only are the sashes effectively supported, 20 but vibration of the sashes in the window frame is prevented while the same can be easily and readily raised or lowered as desired.

What I claim as my invention and desire 25 to obtain by Letters Patent is:—

1. In sliding windows, sashes adapted to slide in the window frame, recesses in the window frame, rollers located in these recesses, annular rings arranged around the 30 rollers, and means for resiliently pressing the rollers against the rings, and the rings

into frictional engagement with the slidable sashes.

2. In sliding windows, sashes adapted to slide in the window frame, recesses in the 35 window frame, supporting frames in these recesses, rollers mounted in the supporting frames, annular rings arranged around the rollers, and means for resiliently pressing the rollers against the rings, and the rings 40 against the sliding sashes.

3. In sliding windows, sashes adapted to slide in the window frame, recesses in the window frame, supporting frames in these 45 recesses, pins engaging in slots in the sides of the supporting frames, rollers mounted on these pins, annular rings arranged around the rollers, and means for resiliently pressing the rollers against the rings, and the rings 50 against the sliding sashes.

4. In sliding windows, sashes adapted to slide in the window frame, recesses in the window frame, supporting frames in these recesses, a removable rear plate to the supporting frame, pins upon which the rear plate is mounted, rollers mounted in forked members, annular rings arranged around the rollers, and means for resiliently pressing the rollers against the rings and the rings 55 against the sliding sashes.

FREDERICK JOHN GARNIER.
